Primary Examiner—Stella Reid
Attorney, Agent, or Firm—Varnell Legal Group**[57] CLAIM**

The ornamental design for a rotor for centrifugal machine, as shown and described.

DESCRIPTION

FIG. 1 is a perspective view of the rotor for centrifugal machine showing my new design;
FIG. 2 is a front elevational view thereof;
FIG. 3 is a rear elevational view thereof;
FIG. 4 is a right side elevational view thereof, the left side elevational view being identical thereto;
FIG. 5 is a top plan view thereof, the bottom plan view being identical thereto;
FIG. 6 is a sectional view taken along line 6—6 of FIG. 2; and,
FIG. 7 is a sectional view taken along line 7—7 of FIG. 2.
